(57) **CLAIM**

The ornamental design for a cartridge, as shown and described.

DESCRIPTION

FIG. 1 is a top front isometric view of a cartridge according to the present disclosure;

FIG. 2 is a bottom rear isometric view thereof;

FIG. 3 is a top view thereof;

FIG. 4 is a bottom view thereof;

FIG. 5 is front view thereof;

FIG. 6 is a rear view thereof;

FIG. 7 is a left side view thereof; and,

FIG. 8 is a right side view thereof.

The broken lines depict portions of the cartridge that form no part of the claimed design. The dot-dash-dot broken lines depict the boundaries of the claim and form no part thereof.
